VEGETABLE SLICER

William E. Gundelfinger, House Springs, Mo., assignor to
The Dazey Corporation, St. Louis, Mo., a corporation of Missouri

Application March 7, 1958, Serial No. 49,941

Term of patent 7 years

(Cl. D89—1)

Fig. 1 is a top plan view of a vegetable slicer showing my new design;

Fig. 2 is an elevational view of one side of the said vegetable slicer;

Fig. 3 is a front elevational view of the said vegetable slicer, and

Fig. 4 is an elevational view showing the opposite side of said vegetable slicer.

I claim:

The ornamental design for a vegetable slicer, substantially as shown.
